UNITED STATES PATENT OFFICE.

JAMES M. DODGE, OF PHILADELPHIA, PENNSYLVANIA, ASSIGNOR TO THE
LINK BELT ENGINEERING COMPANY, OF PHILADELPHIA, PENNSYLVANIA,
A CORPORATION OF PENNSYLVANIA.

DESIGN FOR A SPROCKET-WHEEL.

SPECIFICATION forming part of Design No. 85,192, dated October 15, 1901.

Application filed September 13, 1901. Serial No. 75,352. Term of patent 14 years.

To all whom it may concern:

Be it known that I, JAMES M. DODGE, a citizen of the United States, residing in Philadelphia, Pennsylvania, have invented and produced a certain new and original Design for a Sprocket-Wheel, of which the following is a specification.

My design for a sprocket-wheel is clearly illustrated in the accompanying drawing, which represents a side view of the sprocket-wheel.

The essential feature of the design is the form of the periphery of the wheel.

Referring to the drawing, A is the body of the wheel. a is the rim, projecting from which are a series of teeth b, tapered on each side.

Extending from one side of each tooth is a platform d, and between this platform and an adjoining tooth is a depression e, producing the outline clearly illustrated in the drawing. 20

I claim—

The design for a sprocket-wheel as herein described and as illustrated in the accompanying drawing.

In testimony whereof I have signed my 25 name to this specification in the presence of two subscribing witnesses.

JAMES M. DODGE.
